HOBBYHORSE SWING

Henry O. Gervais, Deerfield, Fla., assignor to Henry Industries, Inc., Wilkes-Barre, Pa.

Filed June 20, 1966, Ser. No. 2,746

Term of patent 3½ years

(Cl. D34—15)

The figure is a perspective view of a hobbyhorse swing showing my new design. The opposite side is substantially a mirror image thereof.

I claim:

The ornamental design for a hobbyhorse swing, substantially as shown and described.
